METHOD OF PRODUCING FLUSH CONTACTS

Henry Kershaw, Belleville, N. J.

Application February 11, 1943, Serial No. 475,538

4 Claims. (Cl. 29—155.55)

My invention relates to a method of producing metal flush contacts or the like, and for securing the same to metal elements.

As is well known, metal flush contacts are made from a solid cylindrical metal blank. This metal blank is placed in a screw machine and the blank is cut to produce the flush contact. This flush contact includes a cylindrical head having an integral shank and a base-disc integral with the shank. This base-disc is subsequently welded to a metallic element or disc of electrical apparatus, such as a radio tube. This operation is time-consuming and expensive.

An important object of the invention is to provide a method whereby the flush contacts can be produced in succession from a metal wire or rod and welded to the desired metallic elements.

A further object of the invention is to provide a method for forming flush contacts upon a metal wire or rod, and weld each flush contact to the desired metallic element, and then sever the welded flush contact from the wire or rod.

A further object of the invention is to subject the metal wire or rod to the action of an electric current, at a point remote from the free end of the wire, to plasticize the wire, and then form the plasticized metal into the head, having a transverse dimension greater than that of the wire and retaining the head integral with the wire.

A further object of the method is to retain the continuity of the wire during the formation of the flush contacts, so that the wire may be properly fed.

A further object of the invention is to provide a method of the above mentioned character, which will exert a pull upon the flush contact after it is welded to the metallic element, to test the strength of the weld, prior to severing the attached flush contact from the wire.

A further object of the invention is to provide a method of the above mentioned character which is continuous in operation and will have a large output, thereby reducing the cost of producing flush contacts and the securing of the same to the metal elements.

A further object of the method is to produce a finished flush contact and to secure the same to a desired metallic element by welding.

Other objects and advantages of the invention will be apparent during the course of the following description.

In the accompanying drawings forming a part of this application and in which like numerals

are employed to designate like parts throughout the same,

Figure 1 is a side elevation of apparatus embodying my invention, showing the wire moved to bring its leading end into contact with the metallic element, the blades and the jaws being in the open position and the upper heating and forming jaws elevated,

Figure 2 is a central vertical longitudinal section through the apparatus, the elements being arranged in the same positions,

Figure 3 is a similar view showing the jaws moved to the inner position, the upper heating and forming jaws elevated, and the blades in the open position,

Figure 4 is a similar view, with the upper heating and forming jaws moved to the lowered position, and the blades in the open position,

Figure 5 is a fragmentary plan view of the guide means for the metallic elements,

Figure 6 is a transverse section taken on line 6—6 of Figure 5,

Figure 7 is a similar view taken on line 7—7 of Figure 5,

Figure 8 is an inner end elevation of the heating and forming jaws and the cold clamping jaws,

Figure 9 is a diagrammatic view showing the circuit connected with the heating and forming jaws,

Figure 10 is a diagrammatic view showing the welding circuit, and,

Figure 11 is a perspective view of the completed flush contact welded to the metallic element.

In the drawings, wherein for the purpose of illustration is shown a preferred embodiment of apparatus for the practice of the method, the numeral 10 designates a base, having guide means 11 to receive metallic elements or discs 12. The guide means has inwardly projecting horizontal flanges 14, engaging all of the top flanges 15 of the element 12, to hold the element against upward vertical movement, when the wire is pulled to test the weld.

At the welding position, the guide means 11 is cut away so that it does not support the element 12, and at this position, the base 10 has an opening 16, to receive a stationary insulating plug 17, receiving a vertically slideable metallic pin 18, carried by a metallic disc 19. The numeral

20 designates a pneumatic cell, which is inflated to the desired pressure. The pin 18 and the disc 19 are light and when the welding between the flush contact and the metallic element occurs, the resilient action of the cell 20 causes the cell to

carry through instantly, without loss of time due to inertia, whereby the contacting parts being welded are instantly brought together.

The metallic elements 12 are preferably fed longitudinally through the guide means by any suitable means, to the welding position, and each metallic element is thereby brought in succession to the welding position. Any suitable means may be employed to effect a step-by-step feeding movement of a line of the metallic elements and to bring each metallic element in succession to the welding position. Suitable means is shown in my copending application 420,876, filed November 28, 1941, which has matured into Patent 2,316,597, under date of April 13, 1943, for Method of and apparatus for welding. This means would have to be slightly modified to accommodate the shape and size of the metallic elements. Any other means may be employed or each metallic element may be manually moved to the welding position and placed upon the pin 18.

Arranged near and above the base 10 are horizontal reciprocatory blades 21, operating in fixed guides and having upper beveled faces 22. These blades are moved inwardly and sever the wire 23' and produce a tapered end 23, to increase the resistance when such tapered end is brought into contact with the metallic element. Any suitable means may be employed to move the blades, in timed order, to opened and closed positions, including cams.

Arranged near and above the blades 21 is a lower pair of cold forming jaws 24, preferably formed of metal. These cold forming jaws are horizontal and reciprocate to opened and closed positions. The jaws 24 may be water cooled. Any fixed means are employed to support and guide the lower cold forming jaws 24 so that they travel in a straight path, and any suitable means may be used to reciprocate them in timed order, including cams and the like. The jaws 24 have their inner opposed ends provided with semi-spherical recesses 25 and semi-cylindrical grooves 26 above and below the recesses.

Rigidly mounted upon the cold forming jaws 24 are heating and forming jaws 27, electrically insulated therefrom, as shown at 28. The lower pair of heating and forming jaws is preferably formed of carbon. Vertical guide pins 29 are rigidly secured to the lower cold forming jaws 24 and extend upwardly above the jaws 24 and pass through openings 30 formed in the jaws 27 and in an upper pair of heating and forming jaws 31, preferably formed of carbon. These guide pins also pass into openings 33^a formed in upper cold clamping metallic jaws 34'. The guide pins 29 carry springs 32, which are insulated from the jaws 27 and 31, and serve to elevate the jaws 31. The upper cold clamping metallic jaws 34' are rigidly mounted upon the jaws 31 and electrically insulated from the jaws 31. The extent of upward movement of the jaws 31 and 34' is limited by adjustable nuts 32', carried by vertical pins 33, and locked in the selected adjusted position by lock nuts 34. The vertical pins 33 are rigidly secured to the jaws 24 and pass through large openings 33^b in the jaws 27 and 31 and are insulated from these jaws.

The upper cold clamping metallic jaws 34' are rigidly secured to and insulated from the jaws 31, as stated. These jaws 34' have openings 33^c, slidably receiving the pins 33. The jaws 34' may be formed of metal and may be water cooled. The jaws 34' have vertical semi-cylindrical grooves 35 to receive and hold the wire 23'. It

is thus seen that each vertical set of jaws 24, 27, 31 and 34' will reciprocate horizontally as a unit, while the upper heating and forming jaws 31 and the cold clamping jaws 34' are shiftable vertically toward and from the heating and forming jaws 27. Any suitable means may be provided to reciprocate the jaws 24, in proper timed order, and all jaws carried thereby are accordingly reciprocated. The lower heating and forming jaws are provided at their inner opposed ends with quarter-spherical recesses 35' and vertical semi-cylindrical grooves 36 beneath the same. The upper heating and forming jaws 31 are provided at their inner opposed end with quarter-spherical recesses 37 and vertical semi-cylindrical grooves 38 above the same. When the upper heating and forming jaw 31 is moved downwardly to contact with the lower heating and forming jaw 27, recesses 35' and 37 are combined to form a semi-spherical recess. The grooves 35, 38, 36, and 26 have the same radii. The recesses 37, 35' and 25 preferably have the same radii although I contemplate having the radius of the recess 25 slightly smaller than the radius of the recesses 37 and 35'.

Means are provided to depress the upper heating and forming jaws 31 including horizontal reciprocatory bars 39, moved inwardly and outwardly in timed order by any suitable means including cams or the like. These bars 39 slide in fixed horizontal guides and carry rollers 40, engaging within recesses 41, having inclined inner ends 42. When the rollers 40 are within the recesses 41 they do not depress the jaws 31, upon the inward or outward movement of the jaws, but when the rollers 40 are moved inwardly with respect to the jaws 31 so that they ride upon the inclined ends 42, they depress the jaws 31, Figure 4.

Means are provided to effect an intermittent step-by-step downward movement of the wire 23' and the length of each step defines the length of the flush contact produced. This wire feeding means may be of any suitable form, but I prefer to employ substantially the wire feeding means shown in my said copending application, Serial No. 420,876. This wire feeding means comprises generally a vertically reciprocatory slide 43, carrying a fiber strip 44 and an opposed metal strip 45, formed of copper or the like and having a guide groove 46 to partly receive the wire. When the slide 43 is moved downwardly the fiber strip is forced into clamping engagement with the wire so that the wire is positively gripped and fed a step defined by the downward step of the slide. When the slide moves upwardly, the fiber strip does not have clamping engagement with the wire but does have sufficient frictional engagement therewith to exert a pull upon the wire to test the strength of the weld produced between the wire and the metallic element. After the slide has reached the uppermost position, and after the strength of the weld has been tested, the wire is severed.

The pairs of jaws 27 and 31 are connected with the opposite poles of a welding circuit 47.

The metallic jaw 35 is connected with one pole of a welding circuit 48 and the metallic pin 18 is connected with the opposite pole of the same circuit.

The practice of the method is as follows:

The metal wire or rod 23' may be stainless steel and may have a diameter of eighty thousandths of an inch (.080"), and is paid out from a spool and is fed vertically and downwardly between

the jaws 44 and 45. The slide 43 moves downwardly while all of the remaining jaws and the blades are in the open position. The wire is thereby passed and guided between the jaws 34', 31, 27 and 24 and in alignment with the vertical grooves of the same. The slide stops in the lowered position and the leading end of the wire is brought into contact with the metallic element 12. The jaws 34', 31, 27 and 24 are now moved inwardly and grip the wire 23', while the upper jaws 31 are elevated. The cylindrical recesses produced by the assembled semi-cylindrical grooves 26, 36, 38 and 35 have a slightly smaller diameter than the wire 23' so that the several horizontal jaws have a suitable clamping engagement with the wire. The diameter of the cylindrical recesses may be from one thousandth of an inch (.001") to two thousandths of an inch (.002") smaller than the diameter of the wire, while these dimensions may be varied.

The degree of pressure that the horizontal jaws exert upon the wire may be regulated and the pressure may be yieldingly applied, if desired. There must be considerable pressure so that the jaws will have clamping engagement with the wire so that the wire is held against the possibility of slipping with relation to the jaws. When the horizontal jaws are moved inwardly, the cold clamping jaws 34' have clamping engagement with the wire and will move the adjacent portion of the wire downwardly toward its leading end when the jaws 31 and 34' are depressed, while the cold forming jaws 24 have clamping engagement with the wire and the previously formed head to hold the adjacent portion of the wire against downward movement toward its leading end. When the jaws 27 and 31 are shifted inwardly and the jaws 31 moved downwardly, the circuit 47 is now closed, and retained closed for a sufficient length of time to plasticize that portion of the wire engaged by the jaws 31 and 27 and arranged between the jaws 34' and 24. The maximum plasticizing action first occurs at the line of contact between the walls of the grooves 36 and 38 and wire. As soon as the plasticizing action is started, the rollers 46 are moved inwardly and depress the upper jaws 31, as the plasticizing action progresses, the clamping jaws 34' rigidly gripping the wire and feeding the same through the wire feed means. The portion of the wire between the recesses 35' and 37 is thereby brought into contact with the walls of the recesses as the recesses 37 move toward the recesses 35', and the plasticizing action increases, between the points A, and about the time that the recesses 37 are moved down to the completely closed position and the closed spherical recess is produced, the plasticizing may be completed or substantially completed, and the closed recess will then form the spherical head B upon the wire. This head is of course integral with the wire. As soon as this occurs the welding or melting circuit is opened and all horizontal jaws are then shifted to the outer position, which occurs after the formed head and adjacent portions of the wire have frozen or become solid, these portions freely separating from the jaws 31 and 21. It is thus seen that the wire is gripped and held against movement near its leading end and gripped at a point spaced from its leading end and the intermediate portion of the wire between these gripped portions is heated and plasticized, at about which time the trailing gripped portion of the wire is moved longitudinally toward the gripped leading portion, whereby the intermediate

plasticized portion of the wire is forced into the forming recess. This forms a spherical head having a greater diameter than the wire, and integral therewith. After the head is thus formed from the wire and is rendered solid, and the horizontal jaws shifted to the opened position, the slide is returned to the upper position, as will be further explained. While all horizontal jaws are open, and the slide 43 elevated, the slide 43 again moves downwardly and advances the wire for the next step, bringing the leading head B opposite to and in alignment with the semispherical recesses 25. The slide remains in the lowered position. All jaws again move inwardly to the closed position while the upper jaws 31 remain elevated. The welding or heating circuit connected with the jaws 27 and 31 is again closed, and the intermediate portion of the wire is plasticized, and the upper jaws 31 are again depressed and force the plasticized portion of the wire into the closed spherical recess, forming the next spherical head B. At this time, the leading spherical head B is held within the spherical recess produced by the semispherical recesses 25 and this head is cold-pressed, thereby further forming the same. The cycle of operation is repeated and spherical heads are formed upon the wire 23 in succession at equi-distantly spaced points. Upon each downward movement of the slide 43, the leading end of the wire beneath the leading head B is brought into firm contact with the metallic element 12, and when all horizontal jaws are moved inwardly the welding circuit connected with the jaw 45 and pin 18 is closed to weld the leading end of the wire to the element 12. The wire 23' depresses the metallic element 12 and the cell 20 is compressed, which occurs before the horizontal jaws are moved inwardly. The resilient action of the cell 20 follows through instantly without loss of time due to inertia, to effect a proper weld. This welding circuit is opened when the weld is completed. While the welding of the leading end of the wire to the metallic element may occur while the horizontal jaws are closed, it may also occur as soon as the wire is brought down to contact with the metallic element, and before the jaws close. When the horizontal jaws open and after the weld has frozen or hardened, the slide 43 moves upwardly and exerts a pull upon the wire to test the strength of the weld. After this pulling action and when the horizontal jaws are opened, the blades 21 move inwardly and sever the wire above and adjacent to the head B, and these blades produce the tapered end upon the leading end of the wire. The severing of the wire upon that side of the head remote from the leading end of the wire produces the finished flush contact which is welded to the metallic element 12. This flush contact includes the head B and shank C. The tapered end of the shank spreads or flattens out during the welding step, as shown at D.

The line of metallic elements 12 is then fed a step and the completed element 12 with the flush contact welded thereto drops or is removed from the line and the next element 12 is brought to the welding position and the cycle of operation is repeated.

As stated, the wire may have a diameter of eighty thousandths of an inch (.080"). The shank C of the flush contact would then have a diameter of eighty thousandths of an inch (.080") or slightly less. The head B of the flush contact may have a radius of five hundred and sixty-five ten thousandths of an inch (.0565")

and the assembled recesses 35' and 37 produce a spherical recess of the same radius as that stated in connection with the head B or slightly smaller, such as from one thousandth of an inch (.001") to two thousandths of an inch (.002") smaller.

It is to be understood that the forms of my invention herein shown and described are to be taken as preferred examples of the same and that various changes in the order of the steps of the method may be resorted to, and that changes in the shape, size and arrangement of parts of the apparatus may also be resorted to without departing from the spirit of the invention or the scope of the subjoined claims.

Having thus described my invention, what I claim is:

1. The method of forming a flush contact attached to a metallic element, comprising feeding a metallic wire longitudinally to bring its leading end into contact with the metallic element, then holding the wire against longitudinal movement, heating the wire at a point remote from the leading end of the wire to plasticize the same while the wire is so held against longitudinal movement, forming the plasticized portion of the wire into a head having a greater diameter than the wire while the wire is so held against longitudinal movement, heating the contacting leading end of the wire and the metallic element to plasticize the same while the wire is so held against longitudinal movement, moving the metallic element toward the leading plasticized end of the wire while the wire is so held against longitudinal movement to weld the same, and severing the wire upon that side of the head remote from the leading end.

2. The method of forming a flush contact attached to a metallic element, comprising supporting the metallic element and applying a force to the same to move it in one direction, feeding a metal wire longitudinally to bring its leading end into contact with the metallic element and shift the metallic element in opposition to said force so that the force will move the metallic element toward the leading end of the wire when the leading end is plasticized, then holding the wire against longitudinal movement, heating the wire at a point remote from the leading end of the wire to plasticize the same while the wire is so held against longitudinal movement, moving that portion of the wire next to the plasticized portion and remote from the leading end of the wire longitudinally toward such leading end and forming the plasticized portion into a head having a greater diameter than the wire while the wire is so held against longitudinal movement, heating

the contacting leading end of the wire and the metallic element to plasticize the same while the wire is so held against longitudinal movement, the metallic element moving toward the leading end of the wire when such leading end is plasticized to weld the same, and severing the wire upon that side of the head remote from the leading end.

3. The method of forming a flush contact attached to a metallic element, comprising feeding a metallic wire longitudinally in a succession of steps and holding the wire against longitudinal movement between each successive pair of steps, bringing the leading end of the wire at the end of each step into contact with a metallic element, applying a force to the metallic element to move it toward the leading end of the wire when such leading end is plasticized, heating the wire at a point remote from its leading end and at the end of such step and while the wire is so held against longitudinal movement to plasticize the same, forming each plasticized portion into a head having a greater diameter than the wire while the wire is so held against longitudinal movement, heating the contacting leading end of the wire and metallic element at the end of each step to plasticize such leading end, the force applied to the metallic element moving the metallic element toward the leading end when the leading end is plasticized to weld the same, and severing the wire at the end of each step adjacent to the head and upon that side of the head remote from the leading end.

4. The method of forming a flush contact attached to a metallic element, comprising feeding a metallic wire longitudinally in a succession of steps, bringing the leading end of the wire at the end of each step into contact with a metallic element, applying a force to the metallic element to move it toward the leading end of the wire when such leading end is plasticized, heating the wire at a point remote from its leading end and at the end of each step to plasticize the same, forming each plasticized portion into a head having a greater diameter than the wire, cold forming each previously formed head at the end of each step and thereby holding the wire against longitudinal movement at the end of each step, heating the contacting leading end of the wire and metallic element at the end of each step to plasticize such leading end, the force applied to the metallic element moving the metallic element toward the leading end when the leading end is plasticized to weld the same, and severing the wire at the end of each step adjacent to the head and upon that side of the head remote from the leading end.

HENRY KERSHAW.
